UNITED STATES PATENT OFFICE.

HERBERT G. ROUNDS, OF BAY CITY, MICHIGAN.

BRACKET FOR USE IN SHINGLING ROOFS.

1,080,658.

Specification of Letters Patent.

Patented Dec. 9, 1913.

Application filed March 19, 1913. Serial No. 755,420.

To all whom it may concern:

Be it known that I, HERBERT G. ROUNDS, a citizen of the United States, residing at Bay City, in the county of Bay and State of Michigan, have invented certain new and useful Improvements in Brackets for Use in Shingling Roofs; and I do hereby declare the following to be a full, clear, and exact description of the invention, such as will enable others skilled in the art to which it appertains to make and use the same.

This invention is a bracket for use in laying wooden shingles and for similar work on roofs.

The object of the improvement is to provide a bracket of small size and simple construction that can be easily applied to or removed from a roof, and that will not only prevent slipping, but will also serve as a means for gaging the rows of shingles as laid, to expose the proper length of shingle to the weather.

With these and certain other improvements that will appear later in the specification, my invention comprises the devices described and the equivalents thereof.

In the accompanying drawings, Figure 1 is a perspective view of a section of shingle roof with a bracket and gage board in place; Fig. 2 is a side view of the bracket, the raised position of the lever being indicated by dotted lines; Fig. 3 is a top plan view of the bracket; Fig. 4 is a rear end view; and Fig. 5 is a top plan view of a bracket fitted with a modified form of lever.

As is clearly shown in the drawing, the device comprises a base 1, preferably of sheet metal, having a central longitudinal upwardly projecting rib 2, on which is pivotally mounted a lever 3, to the rear end of which is pivoted a staple 4, the prongs of the staple passing through openings 5 formed in the rear part of base 1. When the rear end of the pivoted lever is raised, the staple prongs are raised, and when the end of the lever is driven down the prongs are forced downwardly and project below the bottom face of the base.

The bracket is applied as follows: One or more rows of shingles having been laid, the flat pointed end 6 of the base is slid beneath the butts of the upper row of shingles, with the central rib 2 between two shingles. The prongs of the staple are then driven into the lower shingles by driving the rear end of the lever 3 downward with a

hammer. The front or pointed end of the base is prevented from lifting or shifting sidewise by reason of its engagement with the upper row of shingles, and the bracket is prevented from slipping backward by the staple. The rear part of the base 1 is slotted near the base of the tapered point and the metal is folded upward and inward as shown in Figs. 2, 3 and 4. The front end of this folded part of the base forms a stop against the butt of the upper shingle. The inner edges of the folded part form lateral supports for the central rib 2, and at the rear end, the staple, which passes through both the folded end and the base, as shown in Fig. 4, is thus reinforced against bending. Two or more brackets having been placed, as above described, a gage board 7 is laid across them as shown in Fig. 1. This board is equal in width to the weather exposure of the shingles. Since the lower edge of the board rests against the upper end of the pivoted lever 3, any tendency for the board to slip down the roof will cause it to press against the upper or fulcrumed end of the lever, as indicated by the arrow in Fig. 2, tending to drive the staple farther into the roof.

A reinforcing web 8 is preferably secured in the rear part of lever 3, to support it against distortion when a hammer is used to drive the lever down.

To remove the bracket it is only necessary to lift the end of the lever, thus drawing the staple, and withdraw the base from under the shingles.

In Fig. 5 I have illustrated a modified form of handle, consisting in a looped strip of metal 9, but operating in the same manner as above described.

By the means set forth I have produced a simple and inexpensive, yet strong and durable shingling bracket that is easily applied and removed, and that is capable of being used in a number of different situations. For illustration, it is well adapted as a support for scaffold timbers on steep roofs—the method of use being the same as above set forth for shingling.

Having described my invention, what I claim and desire to secure by Letters Patent is—

1. A shingling bracket comprising a flat base adapted to be inserted between two layers of shingles; a centrally disposed longitudinal rib on said base; a stop on said

base; a lever pivotally secured near its front end to said rib and adapted when raised to project beyond said stop, a staple pivotally mounted on the lever near the rear end thereof, said staple passing through openings formed in the rear end of said base.

2. A shingling bracket comprising a flat pointed base formed with a centrally disposed longitudinal rib, the side members of the rear part of said base being folded upwardly and inwardly; a lever pivotally secured near its front end to said rib, the front end of the lever adapted to project beyond the said folded part of the base when the handle is raised, a staple pivotally mounted on the lever near the rear end thereof, said staple passing through open-

ings formed in the rear folded end of said base.

3. A shingling bracket comprising a flat base formed with a centrally disposed longitudinal rib, the side members of the rear part of said base being folded upwardly and inwardly; a lever pivotally secured near its front end to the base, a staple pivoted to the lever near its rear end, said staple passing through openings formed in the rear end of said base.

In testimony whereof, I affix my signature in presence of two witnesses.

HERBERT G. ROUNDS.
